PICKER STICK

David L. Norris, Sr., Greenville, S. C., assignor to
 Norris Brothers, a corporation of South Carolina

Application March 13, 1951, Serial No. 215,287

10 Claims. (Cl. 139—157)

1 This invention relates to picker sticks for looms and particularly to reinforced wooden picker sticks adapted for use with floating pickers, such as the drop box type pickers.

Conventional wooden picker sticks are generally short-lived, the average life of such a stick being only a matter of days. Failure may occur by splitting at the stud hole or breakage in the body of the stick when the stick is subjected to an unusual strain, such as may occur when the shuttle temporarily jams. However, a very common point of failure is the picker-bearing upper end, where splitting may be initiated by breaking or cutting into the body of the stick. This type of failure is particularly characteristic in the use of floating pickers, which are supported on a guide rod and which are provided with a central opening to non-rigidly receive the upper end of the stick.

Failure of the picker stick is costly because it means lost machine time as well as the cost of replacement of a broken stick and sometimes results in a defect in the cloth. Various types of picker sticks have been made in trying to reduce this failure. Sticks of various materials have been tried but have not replaced wooden sticks because wooden sticks have a resilience and elasticity not found in sticks of other materials. To prevent failure at the upper end, various caps and wear surfaces have been tried but have not proved satisfactory.

In prior U. S. Patent No. 2,419,086, there is described a picker stick having a strip of plastic material inserted in an elongated slot formed in the picker stick between the edges. This reinforced stick resulted in longer life without any serious impairment of the necessary resilience and elasticity of the stick. However, the plastic insert did not extend to the ends of the stick and the problem of failure at these areas, while improved, was not completely solved.

In accordance with the present invention, I have now developed a reinforced wooden picker stick which has the desired elasticity of wooden sticks and which, in addition, provides a longer-wearing head for carrying the picker. This stick has a wooden body reinforced internally by a tough, non-frangible insert, similar to that described in the above patent, but which extends in increased width beyond the upper end of the wooden body to form a picker-bearing portion which is integral with the reinforcing portion and which is much tougher than wood.

The details of the present invention are described hereafter in connection with the accompanying drawings, in which:

2 Fig. 1 is a side elevation of a picker stick, embodying the present invention;

Fig. 2 is a longitudinal sectional view of the stick shown in Fig. 1, taken generally along the line 2—2;

Fig. 3 is a longitudinal sectional view of another embodiment of the present invention;

Fig. 4 is a side elevation of the embodiment illustrated in Fig. 3; and

10 Fig. 5 is a transverse section of the picker stick embodying the present invention, taken generally along the line 5—5, as shown in Fig. 1.

Referring now in detail to the drawings, the picker stick of the present invention, indicated

15 generally at 8, has a body portion 10 of tough, straight-grained wood. Extending from the upper end of the wooden body portion 10 to a point adjacent the picker stud hole 12 and in one embodiment (see Figs. 1 and 2) to the lower end of

20 stick 8, is a longitudinal groove having a V-shaped upper portion and a lower portion of uniform width. Disposed within this groove with its sides secured to adjacent sides of body 10 is an insert, shown generally at 14, which includes

25 a picker-bearing portion 16, adapted to extend upwardly from the end of the wooden body 10, an intermediate, wedge-like portion 18 adapted to be received in the upper V-shaped portion of the groove at the end of wooden body 10, and

30 a lower relatively thin, reinforcing portion 20 adapted to provide reinforcement for wooden body 10 without unduly impairing its elasticity and simultaneously secure picker-bearing portion 16 to the remaining portion of the stick.

35 If desired, the reinforcing portion 20 may be coextensive with the length of the wooden body 10, as shown in Fig. 2, or it may terminate short of the picker stud hole 12, as indicated in Figs. 3 and 4. In the latter case, the stick 8 is prefer-

40 ably reinforced at the stud hole 12 by means of rivets 24, or the like, which are disposed transversely of the stick and which extend between the opposing edges on either side of hole 12. Also, in this embodiment, it is desirable that the

45 reinforcing portion 20 and corresponding groove in body 10 be formed with the lower edge extending diagonally upwardly from the inner edge to the outer edge. This reduces the tendency of the insert 14 to be dislodged from wooden body portion 10 by the force of driving the picker.

While I have found that inserts formed of vulcanized fiber give excellent service, however, I use other resinous or plastic materials which have the necessary toughness and elasticity and which are relatively infrangible. The picker-bearing portion 16, the wedge-like intermediate portion

18 and the reinforcing strip 20 of the unitary insert 14 may be molded or extruded as a unit or may be built up of layers of material bonded together by means of a suitable adhesive. In the latter case, it may be desirable to insert a rivet or bolt 26 (see Figs. 3 and 4) through the laminations.

For bonding a vulcanized fiber insert 14 to the wooden body 10, resinous adhesives of the urea-formaldehyde type have been found to be excellent. However, other suitable adhesives may be used, the particular choice depending on the character of the insert.

The upper picker-bearing portion 16 of the picker stick formed in accordance with the present invention is considerably tougher and longer lasting than the commonly available woods. In addition to providing a means of securing the picker-bearing portion 16 to the remainder of the stick, the reinforcing strip 20 strengthens the wooden body 10 to minimize the tendency to split without impairing the desirable resilience of the stick. In the embodiment illustrated in Figs. 1 and 2, the strip 20 provides a particularly effective reinforcement around the picker stud hole 12. This unitary stick is characterized by its simplicity of construction and ruggedness of structure.

The specific examples of insert material and adhesives were given by way of illustration and not limitation, the scope of the invention being defined in the appended claims.

I claim:

1. A picker stick comprising a wooden body portion formed with an elongated slot extending downwardly between the edges from the upper end of said stick and a non-metallic resinous reinforcing insert strip disposed within said slot and adhesively secured to the wooden sides, said insert having an upper end portion of increased thickness extending upwardly above the end of said wooden body portion to form the picker-bearing portion of said stick.

2. A picker stick having a body portion formed of wood reinforced with a tough, non-metallic insert coextensive in width with said stick and extending longitudinally upwardly through said wooden body between the edges thereof from a lower portion of said stick to a point in spaced relation above the end thereof, said insert having an upper portion of increased thickness extending above the upper end of the wood portion of said body adapted to receive the picker.

3. A picker stick comprising a wooden body portion having a slot extending longitudinally from its upper end between the edges thereof, said slot having at its upper end a V-shaped portion, and a reinforcing member of homogeneous, non-fibrous material disposed within said slot and bonded to the wood on either side, said reinforcing member extending upwardly above the end of said wooden body to provide a picker-bearing head of said tough, non-metallic material.

4. A picker stick, according to claim 3, characterized by the further fact that the reinforc-

ing material is a hard, non-frangible plastic having sufficient elasticity to prevent breakage.

5. A picker stick, according to claim 3, characterized by the further fact that the reinforcing material is of hard, vulcanized fiber.

6. A picker stick, according to claim 5, characterized by the further fact that the vulcanized fiber reinforcing material is made up of a plurality of layers of material bonded together and bonded to the wooden body.

7. A picker stick comprising a wooden body portion having a slot extending longitudinally from the upper end of said body portion to a point short of the picker stud hole, said slot being formed at its upper end with a V-shaped configuration; a wear and reinforcing portion of homogeneous, non-metallic material formed with a lower strip-like portion adapted to be received in the lower portion of said slot, an intermediate wedge-like portion adapted to be received in the V-shaped portion of said slot, and an upper picker-supporting portion extending upwardly of said wedge-like portion above the end of said body portion and adapted to receive a picker, said non-metallic insert being adhesively bonded to the slotted sidewalls of said wooden body portion to form a unitary structure; and a pair of reinforcing metallic studs, inserted transversely of said wooden body on opposite sides of said stud hole.

8. A picker stick, according to claim 7, characterized by the further fact that the lower edge of said slot and the corresponding end of said insert are formed to slope diagonally upward from the inner to the outer edges of the stick.

9. A picker stick having a homogeneous, non-metallic, reinforcing core formed with an upper picker-supporting portion, an intermediate tapered portion and a lower relatively thin portion, said intermediate and said lower portions having wooden body members adhesively secured to the sides thereof, said body members extending from the lower end of said stick upwardly to said picker-supporting portion, thereby forming a unitary structure having a lower portion of reinforced wood and an upper portion of homogeneous, non-metallic material.

10. A picker stick, according to claim 9; and further characterized in that the reinforcing core is of laminated vulcanized fiber, wherein the laminations are disposed edgewise in alignment with the wooden body members and are adhesively bonded by means of a urea-formaldehyde glue.
